UNITED STATES PATENT OFFICE.

FRANCIS D. KIRSCH, OF CHERRY TREE, PENNSYLVANIA.

REVERSIBLE ROTARY PUMP.

1,182,571.

Specification of Letters Patent.

Patented May 9, 1916.

Application filed April 9, 1914. Serial No. 830,598.

To all whom it may concern:

Be it known that I, FRANCIS D. KIRSCH, a citizen of the United States, residing at Cherry Tree, in the county of Indiana and State of Pennsylvania, have invented certain new and useful Improvements in Reversible Rotary Pumps, of which the following is a specification.

This invention relates to pumps of the rotary piston type, and the objects are to provide a reversible rotary pump having no stuffing-box or similar packing joints whereby there is effected considerable saving in the first cost as well as the cost of maintenance and repairs; to provide a pump casing having detachable heads provided with openings, which constitute fluid supply and discharge connections, and having their confronting faces dished or concaved or of arcuate form; to provide a rotary pump or piston in the form of a screw whereof the terminals are nested so to speak in the concavities of the casing heads and hence also obtrude upon the fluid supply and discharge passages so that there is no break or interruption in the motive or impelling action and the pump is caused to work at maximum efficiency; and to provide a screw shaft having shoulders or abutments, which cooperate with flanged bushings in the casing heads to take the thrust of the shaft and to obviate the necessity of packing glands.

With these and other objects in view, the nature, characteristic features and scope of the invention will more readily be understood from the following detailed description taken in connection with the accompanying drawing, forming a part hereof, wherein—

40 Figure 1 is a perspective view of a pump embodying features of my invention; and Fig. 2 is a longitudinal-sectional elevational view of the same.

Referring to the drawing, the numeral 5 designates a cylindrical pump casing, which may be mounted in any suitable manner, for example horizontally on the benches 6, and which is provided with flanges 7 for the attachment of the heads 8. The latter are 50 heavy castings having axial openings 9 to accommodate the shaft, and openings 10, which constitute, respectively, fluid supply and discharge connections according to the direction of flow. The heads have a part 55 11, which telescopes the pump casing, and flanges 12 adapted to be secured to the cas-

ing flanges as by bolts 13. The annular part or shoulder 11 constitutes a seat for a packing ring or gasket 14. The heads have their inner or confronting faces dished or concaved or of arcuate form in cross-section, as indicated at 15, the arc passing through the fluid passages so that the terminals 16 of the screw, which are of like arc form or contour, are nested or snugly fitted in the concavities 15 and in their course of travel sweep through the fluid passages so that there is a constant unobstructed flow with no loss or wastage of mechanical energy.

70 The axial or shaft openings 9 are equipped with bushings 17 of Babbitt or other suitable anti-friction metal, said bushings constituting bearings for the shaft 18 and having flanges 19, which bear against shoulders 20. The shaft and its screw may be integrally formed and the diameter of the screw is substantially the same as the inner diameter of the pump casing. The screw is generally provided with three impellers, 80 namely, the terminals 16 and a medial member. The shaft is provided at each terminal end with an annular shoulder or abutment 21, which is accommodated in a recess 22. The ends of the abutments bear against 85 the flanged ends of the soft metal bushings, which consequently take the thrust of the shaft and also coöperate with the traveling abutments to prevent leakage. The shaft may be driven in any suitable manner, for 90 example by a belt pulley 23.

Having described the nature and objects of the invention what I claim as new and desire to secure by Letters Patent is:—

1. The combination of a casing having 95 concaved ends provided, respectively, with fluid supply and discharge connections, a screw-shaft revolvably mounted within the casing and having its terminal blades nested in the concavities thereof, and having abutments which coöperate with the ends of the casing to take the thrust of the shaft and to prevent leakage.

2. The combination of a pump casing, casing heads provided with fluid passages 105 and having their confronting faces of arcuate form, and a rotary pump mounted in said casing and having arc shape terminals adapted to said faces so that their rotative path is through said passages.

3. The combination of a shaft provided with a screw having arc like terminals and

annular shoulders or abutments near the terminal ends, a pump casing including heads having arcuate form confronting faces and fluid connections in the path of the screw terminals, said heads having axial openings for the shaft, and flanged bushings of anti-friction metal innerlying said openings and constituting bearings for the shaft, the arrangement being such that the

bushings coöperate with the abutments to 10 take the thrust of the shaft and prevent leakage.

In testimony whereof I affix my signature in presence of two witnesses.

FRANCIS D. KIRSCH.
